UNITED STATES PATENT OFFICE

ROBERT S. A. DOUGHERTY, OF BETHLEHEM, PENNSYLVANIA, ASSIGNOR, BY MESNE ASSIGNMENTS, TO OPEN HEARTH COMBUSTION COMPANY, A CORPORATION OF NEW JERSEY

OPEN-HEARTH FURNACE

Application filed May 8, 1922. Serial No. 559,381.

The present invention relates to reverberatory regenerative furnaces and particularly to furnaces of this type designed and constructed for use in the manufacture of steel by the open hearth process.

The object of the invention is to provide a reversible regenerative furnace having a novel and improved end construction in which the throat or passage provided for the introduction of combustible gas into the combustion space and for conducting away gases of combustion has associated therewith means for varying its effective area so that when serving as an inlet for unburned gases 15 the throat may be of relatively small effective area and when serving as an outlet passage for the products of combustion of relatively large effective area so that the combustible gases may be introduced at high velocity 20 and with a blow pipe effect, if desired, and the expanded and highly heated products of combustion may pass off freely.

The means employed for effecting the variation in the effective area of the throat 25 consists in a damper insertable into the throat preferably through an aperture in the roof of the furnace. This damper is arranged at an angle to the vertical and transversely of the axis of the throat and slopes down- 30 wardly and inwardly toward the hearth. When the throat is serving as an outlet passage for burned gases the damper is preferably wholly removed but when it serves as an inlet passage the damper may be lowered 35 any distance desired. The gases, particularly the air supplied, flowing toward the combustion space, at the inlet end of the furnace impinge on the inclined rear surface of the lowered damper and an additional advan- 40 tage is realized in that the flow of gas is directed downwardly toward the hearth. The damper accomplishes this function for all ad- justments thereof though of course its influ- 45 ence on the incoming gases is greatest when adjusted to its lowermost position.

The invention is capable of embodiment in different furnace constructions and one em- 50 bodiment is illustrated in the accompanying drawings and below described in detail, by

In the drawings:

Figure 1 is a longitudinal section through a regenerative open hearth furnace having the invention incorporated therein;

Figure 2 is a section on line 2—2 of Figure 55 1, partly broken away; and

Figure 3 is a section on line 3—3 of Figure 1.

The furnace hearth is indicated at 10, the roof at 11 and the side walls at 12. The roof 60 and hearth converge toward the ends of the furnace and the side walls are provided with inwardly off-set portions 13 commonly known as monkey walls, the conduits or passages 14 enclosed between the roof, hearth and monkey 65 walls comprising throats through each of which combustible and burned gases are alternately passed. Gas uptake flues are indicated at 15 and air up-take flues at 16, the gas flues having inwardly and downwardly 70 inclined portions 15' terminating in ports 17 in rear of the throats 14, and the air up-takes 16 terminating in ports 18 opening into the furnace end in rear of the throat. The gas 75 and air up-takes are in communication at their lower ends with regenerators which are not shown but which may be of the usual type. The end portions of the roof above the air ports are downwardly and inwardly inclined so that the air passing into the com- 80 bustion space, which may be under a consider- able pressure and at a relatively high ve- 85 locity, is downwardly directed to envelop the stream of gas from the port 16 and force this gas toward the hearth. Vertically disposed 85 water conducting pipes or conduits 19 are provided to cool and protect the corners of the monkey walls against erosion.

For regulating the effective area of the 90 passage or throat between the gas and air in- let ports and the combustion space, I have provided dampers 20 which are insertable into the throat through slots or apertures 21 in the roof, the edges of the dampers moving in suitable slots in the side walls. These 95 dampers are arranged transversely to the axes of the throats and are inclined in respect to the vertical sloping, as shown in Figure 1, downwardly and inwardly toward the hearth. A motor M connected to the damp- 100

ers by means of a cable 22 may be utilized to raise and lower the same, the cable 22 being passed around a drum 23 arranged to be rotated by the motor, so that they are simultaneously operable. The dampers may be individually operated if desired.

In the operation of the furnace the damper at the inlet end is lowered and the damper at the outlet end is raised as shown in Figure 1. Either the gas or air or both may be supplied under considerable pressure if desired so that the flow of gases through the furnace is at a relatively high velocity, thus promoting rapidity of melting of the charge. In Figure 1 the dampers are illustrated in the positions which they occupy when the left hand end is the inlet end, and it will be seen that the area of the throat has been decreased by the lowering of the damper 20 while at the outlet end the entire throat area is available for the passage of the expanded hot gases so that the draft is unchecked, the air and gas up-takes having sufficient area to easily conduct away the burned gases passing through the throat. A blow pipe effect may therefore be realized without rapidly burning out the furnace. It will be seen that notwithstanding the extent to which the damper at the inlet end may be lowered it will always have a tendency to direct the incoming gases downwardly toward the hearth, thereby causing it to burn where the heat is most needed, and protecting the roof.

Having thus described my invention, what I claim as new and desire to secure by Letters Patent is:

An end construction for regenerative open hearth furnaces, comprising a laterally restricted throat, guideways in the walls at the restricted portion, said guideways extending from the roof part way to the floor, and a damper sliding through the roof in the lateral guideways.

In testimony whereof I hereunto affix my signature.

ROBERT S. A. DOUGHERTY.
